(57) **CLAIM**

The ornamental design for a tripod head, as shown and described.

DESCRIPTION

FIG. 1 is a first perspective view of a tripod head showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion 9 in FIG.

1.

The broken lines shown in the drawings FIGS. 1-8 are included for the purpose of illustrating portions of the tripod head that form no part of the claimed design. The dash-dot line appearing in drawings FIGS. 1, and 9 represent a boundary for the purposes of disclosing areas of enlargement and form no part of the claimed design.

1 Claim, 9 Drawing Sheets
